UNITED STATES PATENT OFFICE.

ALBERT LATHAM, OF BEVERLY, MASSACHUSETTS, ASSIGNOR TO AMERICAN BUTTON & FASTENER CO., OF AUGUSTA, MAINE, A CORPORATION OF MAINE.

METHOD OF ASSEMBLING BUTTONS.

Application filed December 6, 1919. Serial No. 342,968.

To all whom it may concern:

Be it known that I, ALBERT LATHAM, a citizen of the United States, residing at Beverly, in the county of Essex and State 5 of Massachusetts, have invented certain Improvements in Methods of Assembling Buttons, of which the following description, in connection with the accompanying drawings, is a specification, like reference characters on the drawings indicating like parts in the several figures.

This invention relates to the assembling of button parts, it more particularly concerning a method of bringing together to 15 form a button a body portion provided with an opening and a plurality of securing portions therefor.

The usual procedure in making buttons having a perforated pearl or other frangible body or blank and a metal securing eye 20 is to insert the opposite shanks of the eye portion in the blank opening with the ends projecting therethrough, and then upset these ends over the blank, as by spinning or 25 by direct pressure, to hold the parts in co-operation. This is open to several objections. It is usually desirable, especially in the better classes of buttons, as adding to their attractiveness, to have the outer face 30 of the button highly finished, as by polishing the blank and by plating or polishing the central spot of metal. When the parts are assembled as above outlined, the ends of the shanks are necessarily deformed in the upper 35 setting process, so that nothing of their original appearance remains. If, on the other hand, the turned-over ends at the center of the assembled button are polished or plated, the finish of the pearl is almost 40 certainly impaired by the polishing material or by the acid of the plating bath. To guard against the bursting of the blank by transverse strain during the turning over of the ends of the shanks, it is customary 45 to have a substantial clearance between the shanks and the wall of the opening through which they extend. This being true, a proper limiting of the pressure applied to the shank ends, so they shall be upset without 50 crushing the blank, is very likely to leave the shanks unduly loose in the open-

ing. Moreover, as it is difficult to force down, without excessive strain upon the blank, the shank material, either into a recess surrounding the blank opening or into 55 close contact with the face of the blank, there tends to remain a space between the overturned portions of the shanks and the blank, by which wearing apparel may be caught and torn. In view of such conditions, an object of this invention is to provide a method of assembling the elements of 60 buttons, whereby there will be attained secure and intimate union while in a finished condition, without injuriously affecting the 65 ornamentation or polish, and without endangering the blank.

In the accomplishment of this object, a feature of the invention consists in bringing a plurality of securing portions into co-operation with a body portion or blank, and exerting pressure upon opposite extremities of one of said securing portions to expand it and cause the permanent connection of 70 these parts without alteration of the form 75 or finish of the visible surfaces. While this may be accomplished with little rupturing strain of the body, I prefer to so hold said body as to limit its expansion. To increase 80 the security of the connection, one of the securing portions is preferably forced over the body by pressure applied to said securing portions.

Buttons of the type to which this invention is especially applicable sometimes 85 have a depression extending transversely of the body opening in its under side, in which depression one of the securing portions, as the eye, is seated to prevent relative rotation 90 of the parts. To produce proper co-operation of the elements in their assembling, I bring the body and a securing portion together to cause the location of the latter within the former, and then turn said portions relatively in contact with each other 95 until the securing portion and depression co-operate. This turning is preferably by frictional engagement, so that the friction may slip when co-operation is effected, and, therefore, the disengagement need not be 100 timed exactly.

The steps of the invention constituting

my improved method are illustrated in the accompanying drawing, in which—

Fig. 1 shows in side elevation, with parts broken away, the inner securing section or 5 stud of a button;

Fig. 2 is a similar view of the associated securing section or eye;

Fig. 3 similarly illustrates the blank or body portion;

10 Fig. 4 shows in central vertical section the bringing into co-operation the blank and eye, and causing the seating of the depression in the blank upon the eye;

Fig. 5 illustrates in a like manner the 15 holding of the blank;

Fig. 6 is a central vertical section illustrating the step of expanding the stud with- 20 in the eye shanks and blank;

Fig. 7 is a perspective view of the anvil 25 employed for this purpose;

Fig. 8 is a transverse sectional detail taken at the center of Fig. 6; the co-operation of the end of the stud with the anvil being particularly shown;

25 Fig. 9 is a view similar to Fig. 6, bringing out the completion of the step illustrated in the latter; and

30 Fig. 10 is a view, partly in side elevation and partly in vertical section, of the completed button.

In the performance of this method, I prefer to employ button elements consisting of a body portion or blank 10, and securing portions 12 and 14, shown as furnished, respectively, by an eye and a stud or milo. The body may be of pearl, in which case it is cut from sheets to the desired form, or it may be of composition, from which it is molded. It is formed, by boring or in the molding operation, with an axial opening 16, having about one end a concentric recess 18; while adjacent to the opposite end is a transverse slot or depression 20, shown as extending equally on opposite sides of the opening.

45 The eye 12 and stud 14 may be of malleable metal made in any convenient way, as by bending, rolling and stamping. The eye has parallel shank portions 22, 22, the exterior of which are formed as portions of cylinders 50 with such a maximum diameter that, when inserted in the blank opening, they lie in proximity to its cylindrical wall. Upon the inside of the shanks are opposite longitudinal grooves 24, 24, the walls of which are also 55 generally cylindrical. The ends of the shanks are preferably hooked at 26, the inner surfaces 28 of these portions being shown as extending substantially at right angles to the body of the shanks, while each outer surface 30 is inclined to converge toward the 60 surface 28. The stud 14 has a cylindrical body portion, the diameter of which is such that it will fit rather closely within the grooves 24 of the eye shanks, and has at its 65 outer end a head 32 provided with a flat in-

ner surface 34 and a rounded exterior 36, between which is a short wall 35 substantially concentric with the body of the stud and approaching in diameter that of the blank recess 18. The surface 36 may be 70 plated, highly polished, or ornamented in any desired way, since it suffers no mutilation in the process of assembling, only its inner, concealed end being deformed. At the opposite end from the head, the stud has a 75 central conical depression 37 forming a reduced edge about it.

In assembling the parts, opposite clamping jaws 38, 38 are caused to engage the eye to temporarily hold it against movement. The blank 10 is then placed with its opening 16 over the upturned ends of the shanks, and is acted upon by separated engaging members 40, 40, which are rotated as indicated by the arrows. These members have inclined inner contact surfaces 42 for frictional engagement with the outer edges of the blank, thereby rotating it. These members 40 are arranged to first approach the blank and force it over the eye shanks, simultaneously rotating it; and then to retreat to release it. In the movement of approach, the friction between the members 40 and the blank causes the latter to rotate about its axis, so that the grooves 20 will come successively into alignment with the curved portion of the eye, and by the bodily travel of the members be forced together so that upon contact of the blank with the eye, the depressions of the former are seated 90 upon the eye. Then, the friction slips, so that no torsional strain is brought upon the eye and blank, which blank is after an interval released by the recession of the members 40 from it. After the removal of the members 40, a pair of pressure members 41, 41, preferably formed of slightly yieldable material, as fiber, and shaped transversely along the general curvature of the edges of the button blank, are pressed against this to 100 support it against rupturing stresses. The yieldability of the material permits some adaptation to the form of the blank, and therefore avoids injury by the contact of the members with it. Then, through the eye 12 and openings 44 in the jaws 38, a pressure-resisting member or anvil 46 is thrust, having upon one side a pyramidal contact portion 48, which comes into alignment with the blank opening between separated portions 110 of the jaws. The stud 14 is thereupon inserted into the grooves 24 of the eye shanks over the anvil, and a punch 50, having its end generally conforming to the curvature 115 of the exterior of the stud head, is forced against this. The pressure exerted between the punch and anvil expands over said anvil the reduced edge about the stud depression 37, causing it to overlie the curved walls of 120 the eye and fix these two securing elements 130

together. The hooked portions of the shanks are also expanded at 54 to nearly fill the blank recess 18 beneath the wall 34 of the stud head. This more positively locks the 5 hooked portions to the blank, so that all the elements are positively held against separation. During this operation, only slight lateral pressure is exerted by the outer surfaces of the shanks against the wall of the 10 opening 16, but enough to cause the metal parts to almost completely fill the blank opening. The expansion of the hooked ends and the cylindrical wall 35 of the stud head also provides for nearly continuous contact 15 of the stud head and hooked ends with the side wall of the recess. There is consequently no opportunity for lateral play anywhere along the securing portions, and since the wall 34 of the stud head is within the 20 recess, there are no crevices in which fabric may be caught.

Having described my invention, what I claim as new and desire to secure by Letters Patent of the United States is:

25 1. The method of assembling a button having a body portion and securing portions, which consists in bringing the securing portions into co-operation within the body portion, and exerting pressure upon 30 the opposite extremities of one of the securing portions to expand it while leaving the elements over the exposed face of the button in their original condition.

35 2. The method of assembling a button having a body portion and securing portions, which consists in inserting one of the securing portions between divided portions of another securing portion within the body, and expanding the inner securing portion.

40 3. The method of assembling a button having a body portion and securing portions, which consists in inserting one of the securing portions between divided portions of another securing portion within the body, 45 and applying pressure to opposite extremities of the inner securing portion to expand it.

45 4. The method of assembling a button having a body portion and securing portions, one of which is divided and the other arranged to enter between the divisions, which consists in bringing the securing portions into co-operation within the body portion, holding said body portion to limit its 55 expansion, and expanding one of the securing portions.

50 5. The method of assembling a button having a perforated body portion and securing portions, which consists in introducing a securing portion into the perforation from one side of the body portion, causing said receiving portion to overhang the opposite side of the body portion from that at which it is introduced, thereafter, bringing 65 another securing portion into co-operation

with the thus located portion from the opposite side of the body portion, and pressing said securing portions together.

6. The method of assembling a button having a perforated body portion and securing portions, which consists in causing the location of a securing portion in and in engagement with opposite sides of the body portion, bringing another securing portion into co-operation with the thus located portion, and pressing said securing portions together to force said located portion over the body portion.

7. The method of assembling a button having a perforated body portion and securing portions, one of which has a hooked end, which consists in causing the location of the hooked portion in the body opening, bringing another securing portion into co-operation with the hooked portion, and pressing said securing portions together to expand the hooked end over the body portion.

8. The method of assembling a button having a perforated body portion and securing portions, one of which has a hooked end, 90 which consists in causing the location of the hooked portion in the body opening, bringing another securing portion into co-operation with the hooked portion, and pressing said securing portions together to expand 95 the hooked end over the body portion and simultaneously to expand the other securing portion within the opening.

9. The method of assembling a button having a perforated blank, an eye provided 100 with shanks and a stud, which consists in causing the location of the eye shanks in the blank opening, pressing the stud between the eye shanks, and expanding the stud to hold 105 the shanks in the blank and said stud and shanks in engagement.

10. The method of assembling a button having a perforated, recessed blank, an eye provided with hooked shanks and a headed stud, which consists in causing the location 110 of the shanks of the eye in the blank opening with the hooked portions entering the recess, and pressing the stud between the eye shanks with its head in contact with the hooked ends to expand said ends within the 115 recess.

11. The method of assembling a button having a perforated, recessed blank, an eye provided with hooked shanks and a headed stud, which consists in causing the location 120 of the shanks of the eye in the blank opening with the hooked portions entering the recess, and pressing the stud between the eye shanks with its head in contact with the hooked ends to expand the stud between the shanks and the hooked end within the recess.

12. The method of assembling a button having a body portion provided with an opening and with a depression transverse 130

thereto and a securing portion, which consists in causing the location of the securing portion in the body opening, and relatively turning the portions in contact with each other until the securing portion and depression co-operate.

13. The method of assembling a button having a body portion provided with an opening and with a depression transverse thereto and a securing portion, which consists in causing the location of the securing portion in the body opening, and relatively turning the portions in contact with each other by frictional engagement until the securing portion and depression co-operate, and permitting the friction to slip until disengagement occurs.

14. The method of assembling a button having a blank provided with an opening and with a depression transverse thereto and an eye provided with shanks, which

consists in causing the location of the eye shanks in the body opening, turning the blank by frictional engagement until the depression seats itself upon the eye, and permitting the friction to slip until disengagement occurs.

15. The method of assembling a button having a body portion provided with an opening and with a depression transverse thereto and a securing portion, which consists in causing the location of a securing portion in the body opening, relatively turning said portions in contact with each other until the securing portion and depression co-operate, and bringing another securing portion into co-operation with the first located portion.

In testimony whereof I have signed my name to this specification.

ALBERT LATHAM.
